UNITED STATES PATENT OFFICE.

BENJAMIN F. RUNYAN, OF HOUSTON, TEXAS, ASSIGNOR OF ONE-HALF TO JOSEPH O'DONNELL DECUIR, OF HOUSTON, TEXAS.

CRUDE-OIL BURNER.

1,339,579.

Specification of Letters Patent. Patented May 11, 1920.

Application filed June 25, 1919. Serial No. 306,675.

To all whom it may concern:

Be it known that I, BENJAMIN F. RUNYAN, a citizen of the United States, residing at Houston, in the county of Harris and 5 State of Texas, have invented certain new and useful Improvements in Crude-Oil Burners, of which the following is a specification, reference being had to the accompanying drawings.

10 This invention relates to the art of burners and particularly to a burner adapted to burn various grades of crude oil and also for use in connection with very heavy firing in large boilers and the like, though not necessarily, for it is obvious that the burner may be constructed for use in connection with supplying intense heat to smaller boilers and the like.

The invention further aims to provide a 20 burner of this character so constructed that the parts may be easily and quickly disassembled for the purpose of cleaning the interior of the outer casing or tube and also for cleaning the combustion chamber, and 25 also whereby the various parts may be easily repaired or renewed.

The invention further aims to provide means for producing a compound or double 30 whirling spray effect to the oil as it leaves the burner in order to more thoroughly atomize the same to create a greater flame and consequently intensify the heat.

The invention further aims to provide a burner including a chamber for the steam, 35 an innermost chamber or passage for the oil which is intensely heated prior to emanating from the nozzle of the oil passage or chamber, and also a combustion chamber, the wall of which is surrounded by the steam in the 40 steam chamber, thereby greatly heating the combined steam and oil as it is atomized in the combustion chamber, so that by the time the mixture reaches the end of the burner where it is lighted or ignited and where it 45 receives a second atomization, the mixture is thoroughly vaporized or atomized.

The invention further aims to provide means for creating a whirling spray of steam, and also means for projecting diametrically opposite jets of steam to intersect each other directly in the center of the jet of oil as it emanates from the nozzle of the burner, thereby so breaking up the particles of the jet of oil that the oil may be more

thoroughly atomized by means of the whirling spray of steam.

The invention further aims to provide a burner including a tubular body to which any size of burner head may be connected. For instance, various burner heads may be 60 provided having different diameters of passages therethrough for the jet of oil and for the jets of steam, in order to provide various spraying effects and therefore the heads are 65 interchangeable according to the requirements, in fact, according to the size of boiler or other device to be heated.

While the design and construction at present illustrated and set forth are deemed preferable, it is obvious that as a result of a reduction of the invention to a more practical form for commercial purposes, the invention may be susceptible to changes and the right to these changes is claimed, provided they 75 are comprehended within the scope of what is claimed.

The invention comprises further features and combination of parts, as hereinafter set forth, shown in the drawings and claimed.

In the drawings:

Figure 1 is a longitudinal sectional view through the burner constructed in accordance with the invention.

Fig. 2 is an end view showing the relative position of the inclined passages or openings for the steam relatively to each other for creating a whirling spray of steam and also showing the diametrically opposite steam openings, whereby jets of steam may be projected toward and to impinge with each other directly in the center of the jet of oil.

Fig. 3 is a sectional view on line 3—3 of Fig. 1.

Fig. 4 is a sectional view on line 4—4 of Fig. 1.

Fig. 5 is a longitudinal sectional view through a modified construction to that shown in Figs. 1 to 4, inclusive, namely, in so far as the construction of the rear end of the burner is concerned.

Fig. 6 is a sectional view on line 6—6 of Fig. 5.

Fig. 7 is a sectional view on line 7—7 of Fig. 5, and

Fig. 8 is a longitudinal sectional view through a modified construction showing a single means for creating a whirling spray of steam for the jet of oil.

Referring more specially to the drawings, 1 designates a tubular body which may be of any suitable length or any diameter that may be found convenient, and 2 denotes 5 a second tubular body of a relatively smaller diameter whereby it may extend into the main tubular body so as to afford a steam space 3 intermediate the walls of the two bodies. The innermost body is designed to 10 be substantially half the length of the outer or dominant body.

The outer end of the inner tubular body has integral therewith an annular flange 4 which engages the marginal edge of one end 15 of the outer or dominant body. This flange 4 has an annular recess 5 which so engages the end of the dominant body as to hold the flange concentric with the outer body 1, thereby holding the inner tubular body cor- 20 respondingly concentric. The portion of the flange 4 which extends into the outer body 1 is threaded into said body, as shown at 6, to insure a tight joint. However, the threads may be dispensed with, if desired, just so 25 long as the flange is drawn tight against the end edge of the outer tubular body 1. A suitable packing 7 is provided. Also, if desired, the packing may be dispensed with.

The flange 4 at points diametrically opposite each other relatively to the circular interior of the auxiliary tubular body 2 is provided with apertures or openings 8. These openings or apertures act to direct jets of steam at angles toward each other so that the 35 jets of steam may impinge at a point centrally of the vapor or the combined mixture of steam and oil as it leaves the interior of the auxiliary tubular body 2, thereby more thoroughly atomizing the mixture. The 40 flange 4 is provided with additional openings or apertures 9. While certain of these openings 9 are diametrically opposite certain other openings 9, they are disposed upon like inclinations relatively to each other, but which inclinations are at angles 45 to the axis of the passage through the auxiliary body. In other words, the apertures or openings 9 are constructed at angles to the apertures or openings 8, and these openings 9 tend to direct a plurality of jets of steam through the mixture as it leaves the inner auxiliary body, thereby thoroughly 50 atomizing the mixture. It will be noted that certain of the jets of steam will impinge 55 with certain other jets of steam that emanate from the various openings 9. The diametrically opposite openings 8 will cut directly through the mixture while the jets of steam emanating from the openings 9 will 60 cut through the mixture at various angles to the axis of the center of the mixture, that is, as it leaves the mixing chamber 10 of the auxiliary tubular body in a single volume.

The outer casing or tubular body 1 has a 65 lateral tubular extension 11 which may form

a part of the body 1 or be threaded thereinto as shown, though not necessarily, for it is obvious that this extension 11 may be otherwise suitably connected. Any suitable steam supply tube may be connected to the extension 11 to supply steam to the rear part 12 of the steam chamber.

A T-union 13 is mounted on the interior of the dominant tubular body and threaded into one end of the union is a nipple 14 75 which is also threaded into the head plate 15 which is similar in construction to the flange 4 of the inner tubular body 2. In fact, this head plate 15 may be fitted frictionally into the end of the dominant tubular body or 80 threaded thereinto as the case may require. A closure or cap 16 is threaded on the end of the nipple 14 for the purpose of closing the same.

A coupling 17 is threaded into the union 85 13 and in turn is threaded at 18 to the oil tube 19. This oil tube 19 has a nozzle 20. A portion of the tube 19 adjacent the nozzle 20 is threaded through the end head 21 of the auxiliary tubular body 2. By tightening up on the nipple and adjusting the coupling 17 accordingly, the flange 4 of the auxiliary tubular body and the head plate 15 may be drawn securely and tightly in position, thereby affording fluid-tight joints 95 between the parts. A T-union 13 has threaded thereto a tubular coupling 22 to which any suitable oil supply pipe (not shown) may be connected. This coupling 22 holds the union 13 from rotating.

The end head 21 of the auxiliary tubular body is provided with a plurality of openings or apertures 23 which are correspondingly inclined, that is, relatively to the center of the end head. In fact, these openings 23 are arranged approximately tangentially to the center of the end head, but are also arranged just opposite to the arrangement of the openings 9, so as to provide a whirling spray of steam impinging with the jet of oil from the nozzle, the whirling of the spray being just the opposite to the whirling of the spray emanating from the openings 9. It will be seen that while the oil is thoroughly broken up and atomized in the first 105 instance by the whirling spray of steam within the mixing chamber 10, the mixture as it leaves the chamber 10 is again and more thoroughly atomized due to the second 110 whirling spray, just the opposite to the first 115 whirling spray.

In addition to the openings 23, the end head 21 has two diametrically opposite openings or apertures 24, so that the jets of steam will be directed at angles toward each other and impinge with each other directly in the center of the jet of oil emanating from the nozzle, thereby thoroughly breaking up the globules of oil, so that they may be further atomized by means of the whirling 120

spray of steam. The openings 24 are arranged adjacent the tapered extension 25 of the end head so that the jets of steam will be projected along the face of the extension, 5 while the other jets of steam emanating from the openings 23 will be projected tangentially with relation to the extension 25.

As previously stated, steam enters through the pipe or other connection, which is connected to the extension 11, and then into the chamber 12, thoroughly filling the chamber and particularly filling that portion of the chamber between the inner and outer tubular casings. The steam will emanate from 10 the openings 23 and 24 and from the openings 8 and 9. Oil is supplied to the tube 19 through the coupling 22 and then will emanate from the nozzle 20 into the interior of the auxiliary tube or casing 2. Any suitable 15 crude oil of either high or low grade may be employed in connection with the present form of burner.

In Fig. 5, the burner is constructed practically on the same lines and embodies practically the same principle as that shown in 20 Figs. 1 to 4, inclusive. However, in this figure the nozzle from which the oil emanates forms an integral part of the end head 21 of the inner or auxiliary tubular casing 30 and the oil tube or pipe 26 is threaded into an extension 27 of the end head 21. Instead of the construction involving the union 35 13, the nipples 14 and the coupling 17, Fig. 5 discloses a casting 28 which is threaded at 29 into the dominant tubular casing 30. This casting has a passage 31 through which the oil is adapted to pass and into one end of this passage 31 a pipe or tube 26 is threaded as shown at 32, whereby the oil 40 may pass through the pipe or tube 26 and then through the passage 33 of the end head 21. A plug 34 is threaded into one end of the passage 31 for the purpose of closing the same. The casting has an additional 45 passage 35 into which a steam conducting or supplying pipe (not shown) may be connected for the purpose of supplying steam into the steam chamber 12. As in Fig. 1, the steam in the chamber 12 will circulate in 50 the chamber or space 3 between the walls of the auxiliary and dominant tubular casings.

In Fig. 8, the construction of burner is considerably similar to the form of burner 55 shown in the previous figures, particularly Fig. 5, in that a casting similar to that shown in Fig. 5 is employed. In this case, the casting in Fig. 8 is designated similarly to that in Fig. 5, the various parts thereof 60 being correspondingly designated. Also in Fig. 8, the inner whirling head end is dispensed with and instead only a single whirling steam spray is employed at the end of the burner. In this case, the burner head 65 36 has an extension 37 similar to the ex-

tension 27 and into which the oil conducting tube 38 is connected. The burner head 36 is provided with a tapered nozzle 39 which is concentric with the passage or duct 40. The apertures 41 of the head 36 are disposed similar to those in Figs. 1 to 5, inclusive, so as to provide a whirling spray of steam to impinge all about the jet of oil, whereas the openings 42 of the burner head 70 are arranged diametrically opposite to each other, radially with relation to the center of the head, so that single jets of steam projected toward each other at angles may impinge directly in the center of the jet of oil.

The invention having been set forth, what 80 is claimed as new and useful is:

1. In a crude oil burner, inner and outer casings, one in spaced surrounding relation to the other, a burner head connecting the casings at one of their ends, and means connecting the casings at their opposite ends and having means whereby oil and steam may be conveyed to the respective chambers formed by the inner and outer casings, the burner head having a passage and an oil 90 nozzle and provided with passages for directing jets of steam at angles to each other to impinge in the center of the jet of oil from the nozzle and provided with additional passages arranged tangentially to the 95 nozzle for creating a whirling spray of steam toward the jet of oil from the nozzle.

2. In a crude oil burner, the combination with a casing provided with oil and steam chambers, of a burner head having a nozzle 100 for the oil chamber and provided with passages diametrically opposite relatively to the nozzle arranged for directing jets of steam to impinge at angles to each other directly in the center of the jet of oil from 105 the nozzle, said head having an additional plurality of passages arranged tangentially to the nozzle of the burner head for directing a whirling spray of steam toward the jet of oil.

3. In a crude oil burner, the combination with a casing having steam and oil chambers, of a burner head provided with a nozzle communicatively connected with the oil chamber, said nozzle having a plurality of 115 passages communicatively connecting the steam chamber and the atmosphere exteriorly of the burner head, certain of the passages being diametrically opposed and arranged for directing jets of steam to impinge at angles to each other directly in the center of the jet of oil emanating from the nozzle, certain other of the passages being arranged tangentially relatively to the nozzle for directing jets of steam whereby a 125 whirling spray may impinge with the jet of oil.

4. In a crude oil burner, the combination with a casing having oil and steam chambers and provided with a mixing chamber, 130

- 4
- said mixing chamber having adjacent its opposite ends steam spraying means, one spraying the oil, the other spraying the mixture of the oil and steam as it emanates from the mixing chamber, said spraying means including means constructed for causing a plurality of steam sprays, and being arranged to spray at angles, whereby the sprays may impinge at a point tangentially to the oil spray.
5. In a crude oil burner, the combination with a casing having steam and oil chambers and provided with a mixing chamber, of means adjacent the opposite ends of the mixing chamber for spraying the oil and the combined oil and steam at angles toward each other, whereby the sprays may impinge at a point tangentially to the oil spray.
6. In a crude oil burner, the combination with a casing having steam and oil chambers and provided with a mixing chamber, of means adjacent the opposite ends of the mixing chamber for spraying the oil and the combined oil and steam along different tangential lines relatively to the oil spray, said spraying means including means for directing diametrically opposite jets of steam to impinge directly in the center of the jet of oil and in the center of the combined mixture, and means whereby oil and steam may be conveyed to the respective oil and steam chambers.
7. In a crude oil burner, the combination with a casing having steam and oil chambers and provided with a mixing chamber communicating with the oil chamber, one end of the mixing chamber having spraying means disposed for injecting steam sprays into the mixing chamber along tangent lines with respect to and to impinge with the oil spray, one end of the steam chamber having means disposed for injecting a second steam spray along tangent lines different to the first steam spray and to impinge with said mixture of oil and steam.
8. In a crude oil burner the combination with a casing provided with steam and mixing chambers, of means for injecting an oil spray into the mixing chamber, one end of the mixing chamber and one end of the steam chamber arranged and having means disposed for directing converging steam sprays, both of said spraying means being disposed along different tangent lines to the oil injecting means, so that when the mix-

ture leaves the mixing chamber, it will be more thoroughly vaporized by the steam spraying means at one end of the steam chamber.

9. In a crude oil burner, a casing having a mixing chamber and provided with a steam chamber in surrounding relation to the mixing chamber, means at the inner end of the mixing chamber for injecting an oil discharge into the mixing chamber, said inner end of the mixing chamber having passages converging in a direction toward the interior of the mixing chamber to impinge with the oil discharge, for atomizing and mixing the same, one end wall of the steam chamber adjacent the outlet end of the mixing chamber having convergent passages for discharging converging steam sprays to impinge with each other and the mixture as it leaves the mixing chamber. 75

10. In a crude oil burner, a casing having a mixing chamber and provided with a steam chamber in surrounding relation to the mixing chamber, means at the inner end of the mixing chamber for injecting an oil discharge into the mixing chamber, said inner end of the mixing chamber having convergent passages disposed for directing steam sprays along tangent lines with the oil discharge and adapted to impinge therewith 80 for atomizing and mixing the oil. 85

11. In a crude oil burner, a casing having a mixing chamber and provided with a steam chamber in surrounding relation to the mixing chamber, means at the inner end 90 of the mixing chamber for injecting an oil discharge into the mixing chamber, said inner end of the mixing chamber having convergent passages disposed for directing steam sprays along tangent lines with the oil 95 discharge and adapted to impinge therewith for atomizing and mixing the oil, one end of the steam chamber remote from the inner end of the mixing chamber having convergent passages disposed to direct oil sprays 100 along tangent lines with respect to the mixture of steam and oil as it leaves the mixing chamber and to impinge therewith for additionally atomizing the mixture.

In testimony whereof I hereunto affix my 105 signature in the presence of two witnesses.

BENJAMIN F. RUNYAN.
